UNITED STATES PATENT OFFICE.

PAUL MAUSER, OF OBERNDORF-ON-THE-NECKAR, GERMANY.

AUTOMATIC FIREARM.

1,125,578.

Specification of Letters Patent.

Patented Jan. 19, 1915.

Application filed February 12, 1913. Serial No. 747,919.

To all whom it may concern:

Be it known that I, PAUL MAUSER, royal privy commercial councilor, subject of the King of Wurttemburg, residing at Oberndorf-on-the-Neckar, in the Kingdom of Wurttemberg, German Empire, have invented certain new and useful Improvements in Automatic Firearms, of which the following is a specification.

10 The invention relates to automatic firearms in which the trigger is automatically locked when the breech is not closed so that firing is only possible when the breech is closed.

15 The invention consists in improved means for locking and releasing the trigger.

An embodiment of the invention is illustrated in the accompanying drawing, the breech locking mechanism and general construction being similar to that disclosed in my United States Patent No. 1,091,857, dated March 31, 1914.

Figure 1 is a side elevation (partly in longitudinal section) of a pistol provided with a trigger lock in accordance with the present invention. Figs. 2 and 3 illustrate the trigger and locking arm to a larger scale in side elevation and top plan (parts being shown in section) with the breech in closed position. Figs. 4 and 5 are corresponding views illustrating the parts shown in Figs. 2 and 3 in the position which they occupy when the breech is unlocked. Figs. 6 and 7 illustrate the locking bars and slide of the breech locking mechanism in locking and unlocking positions.

In said drawings: reference letter *g* designates the frame of the firearm, *v* a reciprocatory breech block having an abutment *v'* thereon, *b* locking levers, and *s* a slide adapted to move the locking levers *b* into and out of locking engagement with the abutment *v'* of the breech block. A spring *s'* normally presses the slide *s* rearwardly so as to press the locking levers *b* into engagement with the abutment *v'*. The inertia of the slide keeps it from moving when the gun recoils upon discharge and causes the slide to act upon the locking levers *b* in such manner as to throw them outwardly out of engagement with the abutment *v'* to release the breech block. The breech block thereupon opens under recoil, and is closed by the spring *l*.

55 *s* is a trigger pivoted at *s'*, having an arm *k* pivoted thereto at *k'*. The trigger arm *k*

has an extension *k''* thereon which is adapted to coact with the stop *p* which is conveniently formed as a horizontal extension upon a plate *p'* fixed upon a part of the frame 60 and forming a cover for the trigger mechanism. The trigger arm *k* is pressed upon by a spring *k'* in such manner as to move it outwardly when it is free to move.

When the breech is closed and the locking levers *b* are in locking position, the slide is pressed rearwardly by the spring *s'* against the trigger arm *k*. The pressure of the spring *s'* overcomes the pressure of the spring *k'* and causes the trigger arm *k* to 70 move inwardly to the position shown in Fig. 2. In this position the extension *k''* is clear of the stop *p* and is free to move through the space *p''* when the trigger is pulled. Consequently when the breech parts 75 are in locking position the trigger is free, and may be pulled to release the firing mechanism. When, however, the locking levers *b* are not in locking position (as shown in Fig. 7) the slide *s* is in its forward 80 position (see Fig. 4), and does not press against the trigger arm *k*. The spring *k'* is therefore free to press the lever arm *k*, outwardly. In this position the stop *p* is in the way of the extension *k''* and prevents the 85 trigger from turning far enough upon its pivot, when pulled, to release the firing mechanism.

What is claimed is:—

1. In an automatic firearm, the combination of a trigger, a stop, a movable part carried by said trigger and adapted to be moved into and out of engagement with said stop, and a breech locking mechanism adapted to move said movable part on the 95 trigger out of engagement with said stop.

2. In an automatic firearm, the combination of a trigger, a stop, a movable part carried by said trigger and adapted to be moved into and out of engagement with 100 said stop, a spring adapted to press said movable part into locking engagement with said stop, and a breech locking mechanism adapted to move said movable part on the trigger out of engagement with said stop 105 against the action of said spring.

3. In an automatic firearm, the combination of a trigger, a stop, a movable part carried by said trigger and adapted to be moved into and out of engagement with said stop, a breech block, means for locking said breech block, and recoil operated means for 110

actuating said breech block locking means and adapted to move said movable part on the trigger out of engagement with said stop.

5. In an automatic firearm, the combination of a trigger, a stop, a movable part carried by said trigger and adapted to be moved into and out of engagement with said stop, a breech block, locking levers for 10 said breech block and recoil operated means for actuating said locking levers and adapted to move said movable part on the trigger out of engagement with said stop.

15. In an automatic firearm, the combination of a trigger, a stop, a movable part carried by said trigger and adapted to be moved into and out of engagement with said stop, a breech block, locking levers for said breech block, and a recoil operated slide for 20 actuating said locking levers and adapted to move said movable part on the trigger out of engagement with said stop.

25. In an automatic firearm, the combination of a trigger, a stop, an arm pivoted to said trigger and adapted to be moved into and out of engagement with said stop, and a breech locking mechanism adapted to move said pivoted arm out of engagement with said stop.

30. 7. In an automatic firearm, the combination of a trigger, a frame, a movable part

carried by said trigger and adapted to be moved into and out of engagement with said frame, and a breech locking mechanism adapted to move said movable part on the trigger out of engagement with said frame. 35

8. In an automatic firearm, the combination of a trigger, a frame, a stop on said frame, a movable part carried by said trigger and adapted to be moved into and out of engagement with said stop, and a breech locking mechanism adapted to move said movable part on the trigger out of engagement with said stop. 40

9. In an automatic firearm, the combination of a frame, a stop on said frame, a trigger, a movable part carried by said trigger and adapted to be moved into and out of engagement with said stop, a spring adapted to press said movable part into locking engagement with said stop, a breech block, locking levers for said breech block, and a recoil operated slide for actuating said locking levers and adapted to move said movable part on the trigger out of engagement with said stop. 45 50 55

In testimony whereof I have affixed my signature in presence of two witnesses.

PAUL MAUSER.
